UNITED STATES PATENT OFFICE.

FREDERICK PURDY, OF CHICAGO, ILLINOIS.

PROCESS OF MANUFACTURING GAS.

SPECIFICATION forming part of Letters Patent No. 665,266, dated January 1, 1901.

Application filed March 7, 1898. Serial No. 672,960. (No specimens.)

To all whom it may concern:

Be it known that I, FREDERICK PURDY, of Chicago, in the county of Cook and State of Illinois, have invented certain new and useful Improvements in Processes of Manufacturing Gas, of which the following is a full, clear, and exact description, reference being had to the accompanying drawing, forming a part of this specification, in which corresponding letters of reference indicate like parts.

The object of my invention is to provide a simple and cheap process whereby a fixed gas of superior quality for fuel or illuminating purposes may be manufactured by employing any one of various known methods heretofore used for the manufacture of such gas in conjunction with electricity.

To this end my process consists, essentially, in passing the products of the combustion of carbonaceous matter, together with steam and air, into and through a highly-heated converter and therein subjecting the same to the action of currents of electricity generated outside of the converter, all of which is hereinafter more particularly described, and definitely pointed out in the claims.

In the drawing the figure is a central longitudinal vertical sectional view of a gas-converter, showing a construction adapted to carry out my improved process, an electric dynamo being indicated in diagram for supplying the current thereto.

Referring to the drawing, *a* represents a gas-converter which consists of two or more receptacles having a gas-tight outer casing *b*, of sheet metal, having a lining *c*, of any well-known refractory material, preferably fire-brick. Within the first receptacle, which may be cylindrical in shape, is formed a combustion-chamber *d*, in which the coal or other fuel is burned, the usual cone-shaped plug *e* being employed at the top to normally close the feed-opening *f*. An opening *g* at the bottom, closed by means of a suitable plate *h*, luted or otherwise sealed and secured in place, is provided for the removal of ashes. A pipe *i*, connected with an air-compressor or other source of air-supply, is intended to supply compressed air to the chamber *d* to support combustion. Pipes *j* *k*, communicating, respectively, with sources of steam and oil supply, are introduced, preferably, to

a connecting-chamber *l*, which connects the combustion-chamber *d* with a regenerating-chamber *m*. Within the chamber *m* I place 55 an electrode *n*, consisting of one or more plates, preferably of wrought-iron or other suitable metal, in connection with each other or a single cylindrical shell fitted against the lining *c*, by which it is insulated from the 60 outer metal casing *b*. An insulated projection *o*, extending through the outer casing, enables said electrode to be connected, by means of a wire *p*, with the commutator-brush of a dynamo *r*. The other commutator-brush *s* is connected, by means of a wire *t*, with an opposite electrode *u*, which is projected downwardly from the top of the regenerating-chamber *m* of the converter.

Each of the electrodes *n* *u* is provided with 70 a covering *v*, of asbestos, fire-clay, or other refractory material, which is adapted to protect the same from heat and through which is projected a series of metal points *w*, connecting with the respective electrodes. A 75 filling *x*, of any well-known refractory material, is placed in the regenerating-chamber, through the interstices in which the gas is passed to the outlet-passage *y*, from whence it is conducted to any suitable washing and 80 receiving apparatus.

It is well known that gases, especially those rich in carbon, become comparatively good conductors of electricity when their temperature is raised a considerable degree above the 85 normal. I take advantage of this fact and cause the highly-heated products of combustion to become a part of an electric circuit, thus changing the conditions from what they would be were a spark to be projected across 90 the same space filled with gas at a low or normal temperature. In the former case the gas becomes an electrolyte and subject to decomposition by virtue of the electric current. The conditions are so new that the determination of all the reactions can only be made 95 after the most thorough and elaborate investigation; but it is known that ammonia is decomposed by the electrolytic action and its nitrogen made to unite readily with oxygen while nascent, making nitric-acid vapor, which subsequently dissolves in the washing-water. It may also produce hitherto unknown allotropic forms of the constituent elements,

which would account for the harmless effect of such an excess of nitrogen as is used in this process. This may be illustrated by the different well-known forms of various elements, notably that of phosphorus, for example, one form being combustible upon mere exposure to air at ordinary temperatures, while the other, known as "allotropic" phosphorus, is combustible only at a relatively high temperature. In like manner it is well known that ordinary nitrogen is a combustible gas—that is to say, it will unite with oxygen; but the temperature produced by such union being less than the temperature required to maintain combustion it necessarily requires some outside source of heating, whereas in its allotropic form it may combine with oxygen and produce a heat sufficient to maintain such combustion. The current employed may be either alternating or continuous, as either would serve to produce satisfactory results. To produce a thousand feet of gas by this process, about fifteen pounds of bituminous coal are fed into the furnace, and sufficient air to maintain a brisk combustion is introduced. The product formed should then be mixed with about two and three-fourths gallons of crude oil sprayed into it under pressure, together with superheated steam, the amount of which may be varied according to the character of the coal, but ordinarily would be equivalent to about eight gallons of water. The resulting compound should then be subjected to the electrical influence and after cooling washed. The gas produced will be rich in olefins (from twelve to fourteen per cent.) Hydrogen and hydrocarbons will form about twenty-six per cent. There will be about five per cent. of sulfured hydrogen and bisulfid of carbon. Carbonic acid will form about two and one-half per cent. of the whole and nitrogen about forty per cent. The free oxygen will be about two per cent. These proportions of course are variable according to the character of the fuel employed.

Having thus described my invention, I claim—

1. In the process, substantially as described, of manufacturing gas, the passing of the prod-

ucts of combustion, mingled with steam, air and hydrocarbon oil while in a highly-heated state, into an electric field and therewith completing an electric circuit.

2. The method of producing gas consisting in introducing into the heated gases of combustion, a carbonaceous fluid which is transformed into a gas by heat, and finally subjecting the commingled gases to an electrolytic action while in their highly-heated state, substantially as described.

3. The process of manufacturing gas consisting in bringing the products of combustion to a high temperature and subjecting the same to electrolytic action while in their highly-heated state, substantially as described.

4. In the process substantially as described, of manufacturing gas, bringing the products of combustion to a high temperature, and while in their highly-heated state subjecting them to a continuous electrolytic action as distinguished from the action of electric sparks or the thermal action of electrical conductors, substantially as described.

5. In the process substantially as described, of manufacturing gas, the passing of the products of combustion, mingled with steam and hydrocarbon oil while in a highly-heated state, into an electric field and therewith completing an electric circuit.

6. In the process substantially as described, of manufacturing gas, the passing of the products of combustion, mingled with steam and air while in a highly-heated state, into an electric field and therewith completing an electric circuit.

7. In the process substantially as described, of manufacturing gas, the passing of the products of combustion, mingled with air and hydrocarbon oil while in a highly-heated state, into an electric field and therewith completing an electric circuit.

In testimony whereof I have signed this specification, in the presence of two subscribing witnesses, this 21st day of February, 1898.

FREDERICK PURDY.
